UNITED STATES PATENT OFFICE.

VICTOR YORK, OF LOS ANGELES, CALIFORNIA, ASSIGNOR OF ONE-HALF TO WALTER G. BLACK, OF WHITTIER, CALIFORNIA.

PRESSURE CONTROLLER FOR OIL WELLS.

Application filed August 28, 1922. Serial No. 584,919.

To all whom it may concern:

Be it known that I, VICTOR YORK, a citizen of the United States, residing at Los Angeles, in the county of Los Angeles and

5 State of California, have invented a new and useful Pressure Controller for Oil Wells, of which the following is a specification.

This invention relates to oil well drilling equipment and relates particularly to hydraulic rotary drilling equipment.

It is an object of the invention to provide a means by which a tight closure or seal between the rotary drill pipe and the head of 15 the casing may be maintained during the drilling operations in order to permit a pressure to be placed or maintained upon a lubricating liquid in the hole while the drill pipe is being rotated.

20 In the drilling of oil wells by the rotary system a string of drill pipe is rotated in the well, this string carrying the bit at its lower end. The well is kept full of heavy rotary mud during the drilling, this mud serving to "mud up" or temporarily cement 25 the walls of the well and thus sustain them without excessive caving. The mud also tends to "mud up" the formations containing 30 gas or oil and the static pressure exerted by this mud on these formations prevents oil and gas from prematurely blowing into the well which may be disastrous when 35 heavy gas pressures are encountered. In such cases the gas may blow the mud laden liquid out of the well thus relieving the pressure further. Such premature blow-outs often result in the blowing of tools out of the well, and in extreme cases in an entire loss of the well due to fire or to the 40 heavy gas pressure.

It is a further object of my invention to provide means for holding the mud laden fluid in the well while the drilling is in progress and to provide means by which 45 additional mud may be supplied and extra pressure may be applied to the well during the drilling operation.

It is a further object of the invention to provide a device of this character which 50 may be installed with standard equipment now employed, having a piston adapted to be inserted in a drilling string between the drill stem and the top length of drill pipe, the installation of additional lengths of 55 drill pipe as the drilling progresses, being

accomplished by breaking the joint between the piston member and the top lengths of drill pipe and inserting the additional length therebetween.

The especial advantages of my invention 60 and further objects thereof will be made evident hereinafter.

Referring to the drawing which is for illustrative purposes only:

Fig. 1 is a fragmentary elevational section showing the driving equipment and the upper end of a well casing employed in a well being drilled by rotary equipment, this view disclosing an embodiment of my invention in use.

Fig. 2 is a section taken upon a plane represented by the line 2—2 of Fig. 1.

In rotary drilling practice it is customary to place a rotary table 11 upon the derrick platform 12 under which a pit or cellar 13 is dug providing access to the upper end of a well casing 14. Upon the upper end 15 of the casing 14 a lateral outlet fitting 16 is mounted through which the overflow mud rising through the casing may 70 discharge through piping 18 into an overflow sump. By means of a close nipple 19, I mount upon the fitting 16 a flange 20 having a spherical seat 21, upon which rests a spherical bottom flanged member 22, thus 75 providing between the members 20 and 22 a ball joint.

Into the member 22 a tubular member 24 having a cylindrical bore 25 is threaded, this member 24 extending down into the 80 casing 14; and being of somewhat smaller external diameter than the inside of the casing, the tubular member 24 leaves a passage therearound, through which the overflow may pass to the outlet provided by the fitting 16. Threaded into the upper end of the member 22 is a flared nipple 29 which provides a guide to assist in centralizing members being lowered through the tubular member 24 into the casing. Upon the lower 85 end of the drill stem 35 a tool joint box 36 is screwed having a length of pipe 37 extending downwardly therefrom to which is screwed a tool joint pipe 38. Spaced apart 90 upon the pipe 37 by sleeves 40 are mounted a number of piston members 41 carrying piston rings 42 which form a seal with the bore of the tubular member 24, and are 95 slidably and turnably disposed therein, so that the advance and the rotation of the 100

95

100

105

110

line of drill pipe is not interfered with in any way.

In case of striking a pocket of gas, the seal provided by the piston 43, comprised of the smaller piston members 41, prevents the mud from blowing up through the rotary equipment, as it would do where ordinary type of rotary equipment is employed. It may be further seen that it is possible to close down the valve 48, situated in the line 18, so as to resist the reacting pressure encountered in a well.

It is further possible by the use of my device to restrict the overflow of lubricating mud from the well so that the mud pump 50 which delivers lubricating mud through the stand pipe 51 and the hose 52 to the swivel head 53 of the drilling line, may pump a pressure on the interior of the well, so that the mud leaving the drill will be forced out into crevices and voids which may be encountered in the drilling.

When it is desired to place an additional length of drill pipe in the drilling line, the drilling line is lifted through the tubular member 24 to a position above the rotary table 11, and the tool joint between the pipe 37 and the drill pipe 38 uncoupled. The new length of drill pipe is then inserted between the upper end of the line of drill pipe and the pipe 37 which forms the piston member.

The lower piston ring 42 is preferably provided with a packing indicated at 55 for the purpose of preventing leakage of well pressure between the rings and the piston 43.

I claim as my invention:

1. In a device of the character described, the combination of: a casing; a tubular member secured to and extending inside said casing; a string of drill pipe adapted to pass into said tubular member and casing; and means secured between the successive sections of said drill pipe for making a fluid tight joint between the exterior of said drill pipe and the interior of said tubular member.

2. A device as in claim 1 in which means is provided for supplying a fluid pressure to the space between said tubular member and said casing.

3. In a device of the character described, the combination of: a casing; a tubular member secured so as to extend inside said casing; a string of drill pipe adapted to pass into said casing; and packing means for making a fluid-tight joint between the exterior of said drill pipe and the interior of said tubular member, said packing means comprising a hollow member placed between the drill stem and the drill pipe of said string, and members carried upon said hollow member fitting in the bore thereof.

4. In combination: a casing; a tubular

member; means for securing said tubular member to and within said casing; a drill pipe arranged to extend into said casing; a hollow member adapted for disposal in said drill pipe; and members carried by said hollow member for providing a fluid-tight joint between said drill pipe and said tubular member.

5. In combination: a casing; a tubular member; means for securing said tubular member to and within said casing; a drill pipe arranged to extend into said casing; a hollow member adapted for disposal in said drill pipe; piston members arranged on said hollow member and arranged to engage the interior of said tubular member; and spacers arranged on said hollow member between said piston members.

6. An organization as specified in claim 5 in which said pistons are provided with piston rings for providing a positive seal between said pistons and said tubular member.

7. In an oil well, the combination of: a tubular member; means for securing said member in fluid-tight relationship with the walls of the well; a string of drill pipe of such size as to readily pass with its necessary connections through said tubular member; and members carried by said drill pipe adapted to make a fluid-tight connection between said drill pipe and said tubular member.

8. In an oil well, the combination of: a tubular member; a casing secured in gas-tight relationship with the walls of the well; means for providing a gas-tight joint between said casing and said member; a string of drill pipe of such size as to readily pass with its necessary connections through said tubular member; and members carried by said drill pipe adapted to make a fluid-tight connection between said drill pipe and said tubular member.

9. In a rotary oil well drilling device, the combination of: a rotary table; a drill pipe carrying drilling tools, said drill pipe normally projecting downwardly into the well through said rotary table; a tubular member situated below said rotary table and having an internal bore through which said drill pipe and its associated drilling tubes and other equipment may be readily inserted and withdrawn, said tubular member being secured in fluid-tight relationship with the walls of said well; and enlarged portions carried by said drill pipe and fitting into the bore of said tubular member in such a manner as to prevent the egress of fluid therefrom.

In testimony whereof, I have hereunto set my hand at Los Angeles, California, this 22nd day of August, 1922.

VICTOR YORK.
